UNITED STATES PATENT OFFICE.

NATHAN H. SUREN, OF NEEDHAM, MASSACHUSETTS, ASSIGNOR TO THE GAMEWELL FIRE-ALARM TELEGRAPH COMPANY, OF NEWTON UPPER FALLS, MASSACHUSETTS, A CORPORATION OF NEW YORK.

ELECTROMAGNETICALLY-CONTROLLED SWITCH.

1,288,738.

Specification of Letters Patent. Patented Dec. 24, 1918.

Original application filed July 22, 1910, Serial No. 573,291. Divided and this application filed May 8, 1916. Serial No. 98,004.

To all whom it may concern:

Be it known that I, NATHAN H. SUREN, a citizen of the United States, residing at Needham, in the county of Norfolk and 5 State of Massachusetts, have invented an Improvement in Electromagnetically - Controlled Switches, of which the following is a specification.

This invention relates to electromagnetically operated switches, and has for its object the construction of an improved form of switch having a strong actuating spring for operating it, which is adapted to be released easily, so that it may be responsive to a very 10 light current, yet is not liable to be released by a jar. This invention is a division of my 15 application filed July 22, 1910, Serial No. 573,291, which has issued as Patent No. 1,208,044, dated Dec. 12, 1916.

Figure 1 is a front elevation of an electric 20 switch embodying this invention.

Fig. 2 is a vertical section of the same.

Fig. 3 is a fragmentary detail.

The switch embodying this invention is 25 adapted to be locked in closed position and to be released by an electromagnet which is controlled by a very light current. It is here shown as a double-pole switch, and 30 g , g' represent its movable or pivoted blades, which are adapted to engage stationary members, said blades being rigidly connected together.

The movable switch-member has attached to it a strong spring g^{20} , by which it is 35 opened. Said switch-member will be closed by hand against the stress of its actuating-spring, and, when closed, will be engaged by a latch which is subsequently released by the electro-magnet g^2 . As here shown, g^3 represents the latch which is pivoted at g^6 , and 40 controlled by a spring g^7 . It has a projection g^8 adapted to be moved into position to engage the end of an extension g^{10} on the armature-lever g^{12} , of the electromagnet g^2 , 45 when the armature is in its retracted position, as shown in Fig. 3. It has a projection g^9 which is adapted to be struck by a projection g^3 on the switch-member for the purpose of moving the latch into engaging 50 position with the armature. It has a projection g^4 , which, when the latch is moved into such engaging-position, enters a hole

in the projection g^3 , and thereby locks the switch-member in closed position.

When the armature is attracted the armature-lever will be moved to release the latch, see Fig. 3, and as soon as said latch is released, it is moved by its controlling-spring g^7 , and its projection g^4 disengages the projection g^3 , permitting the switch to be opened 60 by its actuating-spring g^{20} . Thus, the switch is manually closed and electro-magnetically released. The several parts are so proportioned that there is a great reduction in leverage, which admits of the employment 65 of a powerful actuating-spring, adapted to be released by a light current, yet the latch is not such as will be released by a jar.

I claim:

1. An electro-magnetically operated 70 switch, comprising a pivoted switch-member, having a locking projection secured thereto and extended rearwardly therefrom having a hole intermediate its length, an actuating-spring connected with said switch-member, a pivoted spring-controlled latch having a projection arranged to enter the hole in said locking projection, and lock the switch-member in closed position, and having a projection arranged in the path of 75 movement of the locking projection to be engaged by the end thereof, for turning the latch on its pivot, and cause its aforesaid projection to enter the hole in the locking projection, and having another projection 80 extended downwardly into the path of movement of the armature-lever of an electromagnet, to be engaged thereby.

2. An electro-magnetically operated 85 switch, comprising a pivoted switch member, a locking member secured thereto and extended rearwardly therefrom having an opening therein intermediate its length, and a latch engaging extremity, and a pivoted, 90 spring pressed latch having a projection 95 thereon arranged to be engaged by the extremity of said locking engagement with said member, and a locking projection arranged to enter the opening in said locking member when said latch is rotated by said 100 member and lock said switch member in closed position.

3. An electro-magnetically operated switch, comprising a pivoted switch mem-

- ber, a locking member secured thereto having an opening therein intermediate its length and a latch engaging extremity, a pivoted latch having a projection arranged to be engaged by the extremity of said locking member to rotate said latch into locking engagement with said member when said switch member is moved toward closed position, and a locking projection arranged to be moved by the rotation of said latch into the opening in said locking member to lock said switch member in closed position, and an abutment arranged in the path of movement of the

projection of said latch to limit the amount of rotated movement of said latch and to 15 restrict, through the projection of said latch, the movement of said switch member toward closed position.

In testimony whereof I have signed my name to this specification in the presence of 20 two subscribing witnesses.

NATHAN H. SUREN.
